United States Patent Office

Des. 222,276
Patented Oct. 12, 1971

222,276

CAT LADDER

Alyn S. Hughes, Jr., 2524 Minnesota Ave.,
Metairie, La. 70003

Filed Sept. 11, 1970, Ser. No. 24,947

Term of patent 14 years

Int. Cl. D30—99

U.S. Cl. D30—42

The figure is a perspective view of a cat ladder showing my new design, the portion partially obscured being similar to that shown on the drawing.

I claim:

The ornamental design for a cat ladder, as shown and described.
